UNITED STATES PATENT OFFICE

133,008

DESIGN FOR A COMBINED PENCIL POINTER AND CLEANER

Arthur B. McCall, Springfield, Ill.

Application January 8, 1941, Serial No. 97,886

Term of patent 7 years

To all whom it may concern:

Be it known that I, Arthur B. McCall, a citizen of the United States and a resident of the city of Springfield, county of Sangamon, and State of Illinois, have invented a new, original, and ornamental Design for a Combined Pencil Pointer and Cleaner, of which the following is the specification, and reference being had to the accompanying drawing, forming a part thereof.

Fig. 1 is a perspective view of a combined pencil pointer and cleaner showing the abrasive side of my new design;

Fig. 2 is a perspective view of the opposite side of Fig. 1 and showing the felt on top;

Fig. 3 is a plan view of Fig. 2; and
Fig. 4 is a side elevation of the design.

My design for a combined pencil pointer and cleaner, as shown, is characterized by the curved ends of the central paddle-like element, which conforms with the curved ends of both the abrasive element on one side and the felt cleaner element on the other side of the design.

I claim:

The ornamental design for a combined pencil pointer and cleaner, as shown and described.

ARTHUR B. McCALL.
